UNITED STATES PATENT OFFICE.

FREDERICK E. ANDERSON, OF PITTSBURGH, PENNSYLVANIA, ASSIGNOR TO UNITED STATES GLASS COMPANY, OF PITTSBURGH, PENNSYLVANIA, A CORPORATION OF PENNSYLVANIA.

DESIGN FOR A DRINKING-GLASS.

48,217.

Specification for Design.

Patented Nov. 30, 1915.

Application filed August 11, 1914. Serial No. 856,313. Term of patent 7 years.

To all whom it may concern:

Be it known that I, FREDERICK E. ANDERSON, a citizen of the United States, and residing at Pittsburgh, in the county of Allegheny and State of Pennsylvania, have invented a certain new, original, and ornamental Design for a Drinking-Glass, of which the following is a specification, reference being had to the drawings forming a part thereof, wherein—

Figure 1 is a side elevation of the glass. Fig. 2 is a top plan view. Fig. 3 is a sectional elevation of a portion of the glass illustrating my new design.

The side wall of the drinking glass is substantially straight from its lower end upwardly to a point near its top edge, at which point a pronounced outward curva-

ture is developed in the form of a concavo convex bulge. This rounded or bulged formation is comparatively shallow vertically and terminates in the top edge, which edge is substantially in the plane of the straight side wall portion. It is thus characteristic of the design that the side of the glass presents a substantially straight line from its bottom to its top edge, save the outward bulge which is adjacent to the top.

I claim:—

The ornamental design for a drinking glass, substantially as shown and described.

FREDERICK E. ANDERSON.
